(57) CLAIM

The ornamental design for a pad for women's pants as shown and described.

DESCRIPTION

FIG. 1 is a rear perspective view of a pad for women's pant showing my new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The light gray portions at the top and bottom are portions of the women's pants and form no part of the claimed design.
